UNITED STATES PATENT OFFICE.

CYRUS M. BRUCE, OF EWING, KENTUCKY.

VALVE-GRINDING TOOL.

1,310,278.

Specification of Letters Patent. Patented July 15, 1919.

Application filed June 30, 1917, Serial No. 177,947. Renewed April 10, 1919. Serial No. 289,133.

To all whom it may concern:

Be it known that I, CYRUS M. BRUCE, a citizen of the United States, and a resident of Ewing, in the county of Fleming and 5 State of Kentucky, have invented a certain new and useful Improvement in Valve-Grinding Tools, of which the following is a specification.

The present invention relates to valve 10 grinding tools, and more particularly to that type adapted to reseat the valves of internal combustion engines and the like.

An object of the present invention is to provide a valve grinding tool capable of 15 grinding a number of valves simultaneously, and which is of such construction that the instrument may be secured to the head or upper end of a cylinder for engagement with the tool to operate the same simultaneously.

Another object of the present invention is to provide a valve grinding machine which is portable; which comprises relatively few parts; which is light in weight 25 and which may be manually lifted into and out of position; and a machine which is adapted to grind a plurality of valves in a relatively short time.

The above, and various other objects and 30 advantages of this invention will be in part described, and in part understood, from the following detailed description of the present preferred embodiment, the same being illustrated in the accompanying drawings, 35 wherein:—

Figure 1 is a side elevation of a valve grinding machine constructed according to the present invention.

Fig. 2 is a top plan view of the same.

Fig. 3 is a horizontal section taken substantially on the line 3—3 of Fig. 1.

Fig. 4 is a fragmentary enlarged sectional view through one of the adjustable bearings for one of the reciprocating elements.

Fig. 5 is a fragmentary sectional view, 45 enlarged, through the rotating disk and the detachable wrist pin mounted therein.

Referring to the drawings, 10 designates a frame which is preferably of rectangular 50 construction, and which extends vertically. The frame 10 is reinforced by the provision of a pair of vertically spaced-apart webs or

braces 11 and 12 which extend longitudinally in the frame 10, and which provide supports for the reciprocating valve engaging elements.

The braces 11 and 12 are provided, in vertical register, with pairs of longitudinally extending slots 13 through which project the opposite ends of tool sockets 14 provided with angular openings in their lower ends into which are engaged the angularly formed shanks of valve engaging tools 15. The base of the frame 10 is provided with a longitudinally extending slot 16 through 65 which the tools 15 project, the tools extending downwardly through the frame 10 and into the valve chambers of an internal combustion engine A, or the like. The valve tools 15 may be of any suitable form and 70 are preferably provided with spade ends for engagement in the kerfs usually formed in the valve head B.

The socket members 14 are adapted for adjustment toward and from each other in 75 the slots 13, and are retained in adjusted position by slidable bearing plates 17 which rest upon the upper faces of the braces 11 and 12, and which are provided at one end with openings therethrough adapted to 80 snugly and rotatably receive the sockets 14 therethrough. The opposite ends of the bearing plates 17 have formed therein longitudinally extending slots 18 through which engage set screws 19, the latter having 85 threaded engagement with the braces 11 and 12. The set screws 19 bind the plates 18 in adjusted position and hold the sockets 14 from movement in the slots 13. As shown in Fig. 1, four bearing plates 17 are employed, the bearing plates engaging the upper and lower ends of the sockets 14, and being carried upon the braces 11 and 12 respectively. The sockets 14 are vertically 90 movable through the bearing plates 17, and are normally urged upward by the provision of yieldable springs 20 which surround the sockets 14 immediately above the lower bearing plates 17. The upper ends of the springs 20 bear against the lower faces of 100 toothed sectors 21 which are arranged upon the sockets 14 between the braces 11 and 12, and which are adjustably secured into position by set screws 22 which engage inwardly

from the flat sides of the sectors 21 and bind against the respective sockets 14. The springs 20 bearing against the sectors 21 urge the same and the sockets 14 upwardly 5 through the bearing plates 17.

The upper ends of the sockets 14 terminate short of the upper portion of the frame 10, and a pressure bar 23 engages across the upper ends of the sockets 14 and extends beyond 10 the latter. The pressure plate 23 is provided at opposite ends with depending stems 24 slidably engaging through apertures suitably formed in the upper brace bar 11. Springs 25 are carried about the stem 24 between 15 the brace bar 11 and the pressure bar 23 to urge the latter upwardly out of engagement with the sockets 14. The upper part of the frame 12 is provided with a pair of set screws 26 which are threaded downwardly 20 through the frame, and which engage at their lower ends against the pressure bar 23. Upon turning the set screws 26 downwardly through the frame 10, the latter urge the pressure bar 23 downwardly 25 against the springs 25, and against the tension of the springs 20 to urge the sockets 14 downwardly through the brace bars 11 and 12, and advance the tools 15 against the valve heads B. The desired pressure of the 30 tools 15 against the valve heads B may thus be obtained, and clamps 27 may be employed at the opposite ends of the frame 10 for engagement with the body of the engine A to hold the frame thereto. In the present 35 instance, each clamp 27 is in the form of a head adapted to engage in an opening of the body A and beneath inwardly extending flanges formed thereon. The head of the clamp 27 is provided with an upstanding 40 pin which passes through the lower end of the frame 10, and which is suitably threaded for the reception of a binding nut 28 upon its upper end. The binding nut 28 engages 45 against the inner face of the frame 10 and holds the latter firmly to the body A of the engine.

A rack bar 29 is arranged in the frame 10 between the braces 11 and 12, and has its opposite ends slidably engaging through the 50 end portions of the frame 10. The rack bar 29 has the teeth thereof facing the teeth of the sectors 21 and is adapted to intermesh with the same. Links 30 are pivoted upon pins 31 intermediate the ends of the 55 links, and which are arranged in the top portion of the frame near the opposite ends thereof. The lower ends of the links 30 are longitudinally slotted and are adapted to extend through openings 32 formed vertically 60 in the rack bar 29 adjacent the opposite ends thereof. Pins 33 are secured transversely through the opposite ends of the rack bar 29 and through the slots in the links 30 to couple the links to the rack bar.

Connecting bars 34 are pivotally connected at one end to the upper ends of the links 30, the connecting bars 34 extending inwardly toward each other and being pivotally mounted at their free ends in overlapping relation upon a wrist pin 35 which projects outwardly from a disk 36. As shown to advantage in Fig. 5, the disk 36 is provided with an opening therethrough adapted to receive the shank of the wrist pin 35, and having a countersink adapted to receive the head of the pin. The disk 36 is provided with a plurality of openings 37 adapted to receive the wrist pin 35 therein, and the openings being arranged at different radial distances from the central axis of rotation of the disk 36. A cross pin 38 or the like is secured through the outer end of the wrist pin 35 to detachably retain the connecting bars 34 thereon.

The disk 36 is secured to one end of a drive shaft 39, the latter being mounted in a bearing 40 upstanding from the frame 10, and having upon its opposite end a preferably peripherally grooved pulley or operating wheel 41 over which is trained a belt 42 actuated by a motor 43, or the like.

In the use of this valve grinding machine, the frame 10 is seated on the upper end of the cylinder A with the valve engaging tools 15 projecting into the valve casings of the cylinder, in the present instance, a beveled cylinder is shown, and the two valve tools 15 may be simultaneously engaged and operated to grind both valves of the beveled cylinder. The clamps 27 are now adjusted to hold the frame 10 upon the cylinder, and the motor 43 is set in operation. The motor 43 turns the shaft 39, and the latter rotates the disk 36, and through the medium of the connecting bars 34, rocks the links 30 and reciprocates the rack bar 29.

As the rack bar 29 is reciprocated the sectors 21 are rocked together with the sockets 14 of the valve engaging elements, simultaneously reciprocating the same, and also reciprocating the valve heads B with which the valve engaging elements engage.

The desired tension may be placed upon the valve engaging elements by adjusting the set screws 26 to move the pressure bars 23 downwardly and thus advance the tools 15 against the valve heads. The bearing plates 17 may be adjusted longitudinally upon the braces 11 and 12 to move the valve engaging elements toward and from each other and thus center the tools 15 in the valve casing.

It is of course understood that any number of valve engaging elements may be mounted in the casing 10 and connected to the rack bar 29 in the manner shown, and that various other changes and modifications may be made in the details of con-

struction, and design, of the above specifically described embodiment of this invention without departing from the spirit thereof, and being restricted only by the scope of the 5 following claims.

I claim:

1. In a valve grinding machine, the combination of a frame, a plurality of valve engaging elements mounted in the frame, operating means connected to the valve engaging elements, means for normally urging the valve engaging elements upwardly in the frame, a pressure bar mounted in the top of the frame for engagement with the upper 10 ends of the valve engaging elements, means for urging the pressure bar upwardly in the frame, and adjusting means in the top of the frame for engagement with the pressure bar to urge the latter downwardly against 15 said valve engaging elements and to advance the latter downwardly in the frame.
2. In a valve grinding machine, the combination of a frame, a pair of vertically spaced-apart braces extending longitudinally 20 in the frame, said braces having vertically registering longitudinal slots therethrough, valve engaging elements mounted in said slots and adapted for movement toward and from each other, bearings mounted on said 25 braces and adapted for adjustment toward and from each other and to support said valve engaging elements, a rack bar mounted for longitudinal reciprocation in the frame, sectors carried upon said valve engaging elements, and intermeshing with the teeth of said rack bar, a pair of links pivotally mounted in the upper end of the frame and having pin and slot connections with said rack bar, an operating shaft, means for 30 turning the shaft, a disk mounted on the shaft, and an adjustable wrist pin carried on the disk and having connection with said links for rocking the same upon the turning of said shaft.
3. In a valve grinding machine, a frame, a plurality of vertically adjustable socket members carried by said frame, means for normally urging said socket members upwardly, a pressure bar engaging the upper 35 ends of said socket members, and adjustable means for forcing said pressure bar downwardly.
4. In a valve grinding machine, a frame, a plurality of vertically adjustable socket members carried by said frame, means for normally urging said socket members upwardly, a pressure bar engaging the upper ends of said socket members, and adjustable means carried by said frame and engaging 40 said pressure bar near its ends for forcing the bar downwardly whereby one end of the bar may be moved a greater distance than the opposite end.
5. In a valve grinding machine, a frame, a plurality of vertically adjustable socket members carried by said frame, means for normally urging said socket members upwardly, a pressure bar engaging the upper ends of said socket members, guide pins carried by said pressure bar near its ends, 45 springs coiled about said guide pins for normally urging the pressure bar upwardly, and adjustable means carried by said frame and engaging said pressure bar near its ends for forcing the bar downwardly, whereby one end of the bar may be moved a greater distance than the opposite end.
6. In a valve grinding machine, a frame, a plurality of vertically adjustable socket members carried by the frame, means for normally urging said socket members upwardly, a pressure bar engaging the upper ends of said socket members, a pair of set screws adjustably carried by said frame and engaging said pressure bar near its ends for forcing the bar downwardly upon adjustment thereof.
7. In a valve grinding machine, a frame, a plurality of vertically adjustable socket members carried by the frame, means for normally urging said socket members upwardly, a pressure bar engaging the upper ends of said socket members, a pair of set screws adjustably carried by said frame and engaging said pressure bar near its ends for forcing the bar downwardly upon adjustment thereof, guide pins carried by said pressure bar near its ends, and springs coiled about said guide pins for normally urging the pressure bar upwardly.
8. In a valve grinding machine, the combination of a frame, a pair of valve engaging elements mounted in the frame, bearings longitudinally adjustable in the frame for said valve engaging elements, sectors carried by said valve engaging elements, a rack bar reciprocable longitudinally in the frame and intermeshing with said sectors, operating means connected to said rack bar for reciprocating the same to actuate the valve 110 engaging elements, means for normally urging said valve engaging elements upwardly, a pressure bar engaging the upper ends of said valve engaging elements, and adjustable means for forcing said pressure bar 115 downwardly.
9. In a valve grinding machine, a frame, a plurality of vertically adjustable socket members carried by said frame, longitudinally adjustable bearings mounted in the frame for said socket members, a pressure bar engaging the upper ends of said socket members, means for normally urging said socket members upwardly, means for normally urging said pressure bar upwardly, 120 and adjustable means for forcing said pressure bar downwardly.
10. In a valve grinding machine, a frame,

a plurality of vertically adjustable socket members carried by said frame, means for normally urging said socket members upwardly, a pressure bar engaging the upper 5 ends of said socket members, adjustable means for forcing said pressure bar downwardly, means for rotating said socket members including sectors carried by said socket

members, a rack bar meshing with said sectors, pivotally supported links having slot 10 and pin connection with said rack bar, a disk, an adjustable wrist pin carried by said disk and having connection with the link to move the rack bar upon rotation of the disk, and means for rotating the disk.

CYRUS M. BRUCE.
